Attorney

UNITED STATES PATENT OFFICE

JOSEPH ZARBA, OF EAST BOSTON, MASSACHUSETTS

STRAIGHTEDGE AND REINFORCING DEVICE

Application filed March 18, 1929. Serial No. 348,002.

The present invention relates to improvements in reenforcing elements for plastered walls and ceilings.

One of the important objects of the present invention is to provide reenforcing units for attachment across the outer faces of the laths, said reenforcing elements being formed with forwardly extending walls, the outer edges of which provide guides in order that the plaster or cement may be applied to the laths to form a wall of uniform thickness.

Another important object of the invention is to provide a reenforcing device of the above-mentioned character wherein the same is provided with openings in the forwardly extending wall or rib through which the plaster or cement passes when applied to the laths, so that said device will act as a key for the plaster to prevent the same from cracking or falling.

Another important object of the invention is to provide a device of the above-mentioned character that will at all times be positive and efficient in carrying out the purposes for which it is designed, the same being further simple in construction, inexpensive, strong and durable.

Other objects and advantages of the invention will become apparent from the following description when taken in connection with the accompanying drawing.

In the accompanying drawing wherein like reference characters indicate corresponding parts throughout the same:

Figure 1 is an elevational view of a wall that is partially plastered, showing my improved straight edge device attached to the outer faces of the laths.

Figure 2 is a transverse section taken approximately on the line 2-2 of Figure 1 and drawn on an enlarged scale; and

Figure 3 is a fragmentary detail perspective view of the straight edge device per se.

In the drawing, wherein for the purpose of illustration is shown the preferred embodiment of my invention, the numeral 1 designates generally the parallel, spaced studdings that are commonly provided in the ordinary building structure to form the

walls. Nailed across the spaced studdings in the usual manner are the wooden laths 2. My reenforcing device is shown generally at 3 in Figure 3 and the same is formed from a strip of sheet metal that is bent back longitudinally upon itself to form the abutting walls 4 and 5.

Those abutting walls are further formed with the vertically spaced aligned elliptical-shaped openings 6, the purpose of which will be presently described. While I have shown and described these openings as being preferably of elliptical shape, it is to be understood that I do not wish to limit myself to the particular shape of these openings.

The free edge portion of the wall 5 is bent laterally as indicated at 7 and this laterally disposed portion is formed at spaced intervals along its length with the transverse slits whereby to provide a plurality of attaching flanges denoted by the reference character 8. The alternate ones of these flanges are bent laterally over the free edge of the wall 4 so that the attaching flanges are arranged in staggered relation on opposite sides of the abutting walls and each flange is formed with an opening 9 for receiving any suitable fastening means that may be driven into the studding 1 as shown in Figure 2.

As many of these reenforcing members 3 may be employed as is desired, the same being arranged at spaced intervals and the flanges 8 extend across the outer faces of the laths 2. The joined forward edges of the walls 4 and 5 provide what I term a straight edge 10 and furthermore constitutes a guide for determining the amount of plaster or cement that is to be applied to the laths.

In Figure 2, there is shown the rough coating A of plaster as applied to the laths, and the front face of this rough coating lies substantially flush with the straight edge 10 and furthermore a certain amount of the plaster is keyed in the spaced openings 6. By removing a board having a straight edge across the adjacent edges 10, a coating of uniform thickness will be insured. A finishing coat of plaster may then be applied to

the front face of the rough coating A so as to cover over the edges 10 of the reenforcing members 3 so that said reenforcing members will be entirely embedded within the plastic coating.

5 It will thus be seen from the foregoing description, that I have provided a device that functions not only as a means for engaging the thickness of the plaster that is applied to the wall but also as a reenforcing means for the plaster whereby to prevent cracking and falling of the same.

10 The simplicity of my device enables the same to be constructed at a very low cost and furthermore the same can be attached 15 during the forming of the walls or ceilings without any difficulty.

15 While I have shown the preferred embodiment of my invention, it is to be understood that minor changes in the size, shape and arrangement of parts may be resorted to without departing from the spirit of the invention or the scope of the appended 20 claims. Obviously, the present device may be used to advantage in the spaces around window and door openings, and for ground 25 for base boards.

I claim:

1. A reenforcing element for plastered 30 walls formed from a single strip of metal that is bent back upon itself longitudinally to form opposed walls, and laterally extending flanges at the inner edges of the walls for securing the reenforcing element across 35 the front faces of the laths to which the plaster is applied, the flanges being formed along the inner edge of one wall, and alternate flanges bent laterally and firmly over the free edge of the opposite wall, the joined 40 forward edges of the opposed walls constituting a straight edge and gage for obtaining a plastered wall of uniform thickness.

2. A reenforcing element for plastered 45 walls formed from a single strip of metal that is bent back upon itself longitudinally to form opposed walls, and laterally extending flanges at the inner edges of the walls for securing the reenforcing element across 50 the front faces of the laths to which the plaster is applied, the flanges being formed along the inner edge of one wall, and alternate flanges bent laterally and firmly over the free edge of the opposite wall, the joined 55 forward edges of the opposed walls constituting a straight edge and gage for obtaining a plastered wall of uniform thickness, the opposed walls being formed with spaced alined elliptical openings to which some of 60 the plaster is disposed to key the reenforcing member in the plaster.

In testimony whereof I affix my signature.

JOSEPH ZARBA.
